Des. 202,785
Patented Nov. 9, 1965

202,785

ELECTRICAL STRAIN INSULATOR OR SIMILAR ARTICLE

Fred C. Vose, Severna Park, Md., assignor to General
Electric Company, a corporation of New York

Filed Aug. 21, 1964, Ser. No. 81,391

Term of patent 14 years

(Cl. D26—10)

Fig. 1.

Fig. 2.

FIGURE 1 is a side elevational view of an electrical strain insulator or similar article, showing my new design, the opposite side being substantially a mirror image thereof; and FIGURE 2 is an end elevational view, the opposite side end being substantially a mirror image thereof.

I claim:

The ornamental design for an electrical strain insulator or similar article, as shown and described.
